UNITED STATES PATENT OFFICE.

EMMET P. GRAY, OF DETROIT, MICHIGAN.

STRAINER.

975,687.

Specification of Letters Patent. Patented Nov. 15, 1910.

Application filed December 20, 1909. Serial No. 534,198.

To all whom it may concern:

Be it known that I, EMMET P. GRAY, a citizen of the United States, and residing at Detroit, in the county of Wayne and State of Michigan, have invented a new and useful Strainer, of which the following is a specification.

This construction relates to means for separating impurities from liquids, particularly from gasoline, and the object of this invention is to provide a device of this kind with screens that may be readily removed and that may be cleaned by a return flow of the liquid.

15 In the accompanying drawing, Figure 1 is a vertical section of my improved strainer. Fig. 2 is an elevation, Fig. 3 is a bottom plan, and Fig. 4 is a top plan of the same. Figs. 5 to 8 inclusive represent different positions of the valve. Figs. 9, 10 and 11 show screens.

Similar reference characters refer to like parts throughout the several views.

The body 1 of the strainer is formed with a threaded internal ring 2, a threaded connection 3 for the inlet pipe, a threaded connection 4 for the outlet pipe, a tapering seat 5 for a valve plug 6, passages 7, 8 and 9 for the liquid, and a seat 10 for the cap. The 25 valve plug 6 is of a well known three-way type and has a handle 11, passages 12, 13 and 14 meeting at the center, and a threaded end 15 which receives the nut 16 and washer 17.

35 The upper end of the body is closed by a cap 20, and a gasket 21 may be employed to insure a tight joint between the cap and the seat 10. Depending from the cap is a hollow body 22 having a circumferential 40 groove 23 which connects with the bore of the body by means of passages 24. The lower end of the body is threaded to engage in the ring 2. The body 22 is chambered to receive the desired number of spacing rings 45 25, between which may be placed the screens 26, 27, 28, 29 and 30, of any desired material, such as woven wire, perforated sheet metal, cloth or soft leather. The preferred arrangement is a coarse metal screen 26 at 50 the bottom, a finer screen 27 next thereto, a still finer screen 28 above that, and so on. Chamois skin may be employed for the last screen 30 and muslin for the screen 29 adjacent thereto. The screens and spacing 55 rings are held in position in any desirable

manner, the screw threaded ring 31 being a very satisfactory device for this purpose.

This strainer is especially adapted to be placed between the storage tank and the carbureter of gasoline engines. When the engine is to be started, the valve plug 5 is turned to the position shown in Figs. 1 and 5, permitting the gasoline to flow through the passages 7, 14, 12 and 8 to the screens. The coarsest screen will intercept the 60 coarser particles and each of the finer screens in turn those less coarse. When the engine is stopped, the valve may be turned to the position shown in Fig. 6, when the gasoline will flow back from the carbureter through 65 the screens, carrying down the impurities which have lodged against the lower sides of the several screens, out through the passages 8, 14, 13 and 9 into some proper receptacle. When it is desired to leave the 70 gasoline in the carbureter, but drain the tank, the plug may be placed as shown in Fig. 7, when the liquid will flow through the passages 7, 13, 12 and 9. In Fig. 8 is 75 shown the position in which the plug will 80 be left when the engine is idle, all the passages being open to permit perfect drainage. It will be noticed that all the screens can 85 be removed and replaced without disturbing any of the connections, and that the carbureter can be drained preparatory to such removal so as to obviate any waste of gasoline. It is also understood that any other liquid can be readily strained while in passage by this device. The material 90 composing the straining disks will depend upon the liquid being strained. It will be noticed that should the flow of the liquid through the strainer be in the opposite direction, the impurities would be collected within the 95 shell 22, and in such case, the relative positions of the screens should be reversed.

Having now explained my improvements, what I claim as my invention and desire to secure by Letters Patent is:—

1. In a strainer, the combination of a cylindrical body having a threaded interior ring intermediate its ends and an inlet connection and a drain passage at its lower end, a valve to control the flow through said passages, a cap for the upper end of said body and a shell below said cap having a plurality of screens mounted within its bore and having its end threaded to engage the threaded ring of the strainer body, said body

having an outlet for the strained liquids and said shell having passages to permit the liquid to pass through the same.

2. In a strainer, the combination of a body having an inlet connection and a drain passage at its lower end, a valve to control the flow through said passages, a cap for the upper end of said body, and a shell below said cap having a plurality of screens mounted within its bore, said body having an outlet passage for the strained liquids and said shell having passages to permit the liquids to pass through the same.

3. In a strainer, the combination of a

hollow body having a closed end and having inlet and outlet passages, a removable cap for said body, a shell connected to said cap and having a passage connecting its interior to the outlet passage of the body, a series of spacing rings mounted within the shell, and a screen between each two rings.

In testimony whereof, I have signed this specification in the presence of two subscribing witnesses.

EMMET P. GRAY.
